UNITED STATES PATENT OFFICE.

JAN SZCZEPANIK, OF VIENNA, AUSTRIA-HUNGARY, ASSIGNOR TO SOCIÉTÉ DES INVENTIONS JAN SZCZEPANIK & CIE., OF VIENNA, AUSTRIA-HUNGARY, A FIRM.

MULTICOLOROUS WOVEN FABRIC.

No. 824,158.

Specification of Letters Patent.

Patented June 26, 1906.

Application filed October 11, 1901. Serial No. 78,381.

To all whom it may concern:

Be it known that I, JAN SZCZEPANIK, a subject of the Emperor of Austria-Hungary, residing at Vienna, in the Province of Lower Austria, in the Empire of Austria-Hungary, have invented certain new and useful Improvements in Multicolorous Woven Fabric; and I do hereby declare the following to be a full, clear, and exact description of the invention, such as will enable others skilled in the art to which it appertains to make and use the same.

This invention relates to a woven fabric the system of threads of which running in one direction is formed by successive groups of threads which possess the colors corresponding to the three primary colors—blue, green, and red—whereas the other system of threads which is crossing the said thread system perpendicularly is formed by white threads or, if desired, by white and black threads. In this manner, owing to the total effect of the colored threads corresponding to the three primary colors and with the aid of the white or of the combination of white and black threads intended for producing the gradations of tints, the pattern of the fabric appears to the eye in the natural colors and tints of the original, similarly to a colored photograph produced after the known method of Jolly, or of McDonough, described in his United States Patent No. 611,457. The woven fabric is thus composed of groups arranged in juxtaposition and composed each of three colored threads corresponding to the three primary colors and of white or of white and black threads crossing the first-named groups. For the color effect which is to be obtained it is quite indifferent whether the system of colored threads corresponding to the three primary colors will constitute the warp of the fabric or the weft of the same. It is, however, advantageous to arrange this system of colored threads as the warp of the fabric—that is to say, to use the colored threads for the warp and to produce the gradation of tints by a white weft—because the warp-threads can be arranged more densely and for this reason a better total effect of the three threads which correspond in color to the three primary colors can be obtained.

A tissue or fabric produced in the above described manner would, however, possess

too loud a coloration, and for this reason it 55 is advisable to use in combination with the said three colors a fourth color—for instance, black—which will be a weft-thread when the warp-threads are of the primary colors and a warp-thread when the weft-threads are of 60 the primary colors, as the case may be. If now the primary colors are given by the warp, the first white weft-thread will shade all light-colored parts of the fabric, while the following black weft-thread will shade all 65 dark places of the fabric. The weft is therefore alternately white and black. The primary colors may also be expressed in the fabric conjointly both by the warp and by the weft, this arrangement being of advantage, 70 for instance, in the case of two-ply fabrics.

I claim—

1. A colored fabric in which the threads in one direction are of the primary colors only 75 and transverse white, to produce designs simulating natural colors, substantially as described.

2. A colored fabric in which the threads in one direction are of primary colors only, together with transverse white threads to produce high light and black threads to produce shadows, substantially as described.

3. A colored fabric in which the warp-threads are arranged in sets of three, each 85 thread of a set being of a different primary color, and white weft-threads to produce designs simulating natural colors.

4. A colored fabric in which the warp-threads are arranged in sets of three, each 90 thread of a set being of a different primary color, and weft-threads of white to produce high lights and black to produce shadows, substantially as described.

5. A multicolored fabric having continuous threads in one direction of primary colors and transverse threads, the primary-colored threads being arranged above the transverse thread to place the colors in juxtaposition to produce the designs in colors simulating natural color effects, including the mixed colors.

In testimony that I claim the foregoing as my invention I have signed my name in presence of two subscribing witnesses.

JAN SZCZEPANIK.

Witnesses:

JOSEF RÜBASCH,
